UNITED STATES PATENT OFFICE

ROBERT T. ROMINE, OF MOUNT CLEMENS, MICHIGAN

METHOD AND APPARATUS FOR HANDLING METAL

Original application filed August 10, 1926, Serial No. 128,396. Divided and this application filed April 7, 1927. Serial No. 181,865.

This invention relates to a method and apparatus for handling metal, such as sheet metal, at the mill or other production source, and particularly concerns the forming and binding of the metal into individual packs or units as the constituent sheets issue from the final operation at the mill, to be placed in storage or shipped in carriers. Moreover, the present invention relates to the handling of sheet metal in packs or units of such weight or character as to render it impracticable or impossible to handle them by hand without first breaking up the packs or units and requiring the separate handling of the constituent parts thereof. This invention is a division of the invention shown on and described in my co-pending application Serial No. 128,396 filed August 10, 1926, now patent No. 1,745,044, Jan. 28, 1930.

An object of the invention is to provide an efficient and practicable method of handling sheet metal, together with an improved apparatus for carrying out the method, at the mill, or other production source, for the purpose of stacking the metal sheets as they issue from the final operation upon an improved buck or supporting device to form a pack or pile of the desired size or weight, binding the pack into a unit and conveying it to destination, such for example as to a storage place on a freight car for shipment.

Another object of the invention is to provide an improved buck or device for receiving and supporting the metal sheets as they issue from the final operation at the mill, with the sheets maintained in an upright position at an incline to the vertical and resting on their edges, and to so construct the buck or device as to permit the application to the pack or pile of metal sheets while supported thereby of binding devices adapted to bind the constituent sheets together and maintain them against relative displacement during the subsequent handling or shipment of the pack.

In accordance with my present invention I provide, preferably, binders which are adjustable and fully flexible to adapt them for use in the binding of packs of varying sizes, and provide certain of said binders with

means to permit the attachment thereto of a crane hook or other hoisting medium, whereby the bound pack may be picked up and transported bodily by the crane. Certain of the binders may be provided with inserts of relatively soft material which are adapted to extend beneath the pack of metal sheets in engagement with the edges thereof to support the sheets and likewise assist in restricting the relative longitudinal movement of the sheets.

Other objects of the invention will be apparent from the following description and appended claims when taken in connection with the accompanying drawings, wherein like reference characters indicate similar parts in the several views.

In the drawings:

Fig. 1 is a perspective view of my improved loading apparatus or buck with a pack of metal sheets being formed thereupon.

Fig. 2 is a side elevation of a bound pack or bundle in position upon the buck of Fig. 1.

Fig. 3 is an end elevation of a completed or bound bundle.

Fig. 4 is a sectional view taken along the lines 4-4 of Fig. 2 after the pack has been removed from the buck.

Fig. 5 is a fragmentary perspective view of the parts of one of the binders or bracing devices.

Fig. 6 is a fragmentary detail perspective view illustrating one of the devices for enabling the pack or bundle to be lifted by means of the stack lifter or crane.

Fig. 7 is a diagrammatical view showing the step of transferring a bound pack from the buck to storage or elsewhere.

Fig. 8 is a diagrammatical view showing one of the bound packs in position upon the storage warehouse floor and another pack being transferred from the floor to a lift truck platform.

Fig. 9 is a diagrammatical plan view of one preferred layout of a landing or loading dock illustrating the manner in which a bound pack is transported from a lift truck platform into position within a freight car.

Fig. 10 is a side elevation of my improved stack lifter being transported upon a lift truck platform.

Fig. 11 is a perspective view of the interior of a freight car showing the stack lifter supporting a pack of metal sheets after its removal from the lift truck platform.

Fig. 12 is a fragmentary perspective of one end of the freight car with two packs or bundles of metal supported upon the floor thereof.

Fig. 13 is a side elevation of one of the 10 packs of Fig. 12.

Fig. 14 is a diagrammatical view illustrating the action of the bracing devices or binders on the pack of sheets in the car.

Before explaining in detail the present 15 invention, and the method or mode of operation embodied therein, it is to be understood that the invention is not limited in its application to the details of construction and arrangement of parts illustrated in the 20 accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several 25 claims hereto appended or the requirements of the prior art.

30 In Figs. 1, 2 and 7 I have shown my improved buck or loading apparatus which may be positioned at the mill in such manner that the sheets after the final operation may be handled by the workmen and placed in position upon the buck or loading device to be bound into packs or units while supported thereby.

The buck or loading platform is shown as a whole at X and comprises preferably, an 10 inclined base and an inclined back support at right angles to the base so that when the sheets forming the pack are placed upon the base, they will be canted or inclined at an angle to the vertical. The base may comprise a series of spaced wedge-shaped blocks or timbers 15 arranged in parallelism, and a 15 plurality of channel bars 16 one of which is provided for each of the blocks 15 and mounted thereupon. Four such blocks and 20 channel bars are provided as shown in the drawings, although it is to be understood that any desired number of such members may be employed, dependent upon the particular size of the sheets to be formed into a 25 pack. Mounted upon each channel 16 is an upright channel post 17, the pairs of channels being united together by means of an angle bar 18. Connected with each pair of channels 16 and 17 and serving to brace the same, is 30 a gusset plate 19 secured to the channels 16 and 17 by means of rivets or the like 20. The upright channel bars are connected together at the top thereof by means of a metal bar 21, the bar and channels being riveted together. It will be seen that the pairs of chan-

nels are maintained in spaced relation and form an integral and rigid supporting table for the metal sheets constituting the pack S.

As the finished sheets issue from the machines or the finishing process at the mill, 70 workmen place such sheets in position upon the spaced base channels 16, with the sheets resting on their edges and in an inclined position engaging the back supports or channels 17. The requisite number of sheets are placed 75 upon the buck until a pack, such as the pack S, has been formed.

The next step of my method relates to the binding of the pack by means of suitable binding devices such as shown at B. 80

The binding or clamping apparatus for the pack, in the present instance, may if desired comprise identical sets of devices at opposite ends of the bundle or pack S, and in addition thereto a central device preferably located 85 midway of the bundle. The end clamping devices or binders each comprises a pair of vertical clamping or lifting bars 25 and 26 one at each vertical side of the pack, these bars being preferably constructed in the form of steel I- 90 beams. Riveted to the lower end of each bar 25 and 26 is a stirrup or strap 27 which comprises a steel bar riveted at the opposite ends thereof to opposite flanges of the I-bar and bent around the lower end of the bar in loop 95 form to provide a pair of openings or pockets at the opposite sides of the bar. Loosely fitting into these openings or pockets and extending crosswise or transversely beneath the pack are a pair of space parallel steel bars 100 28. Each bar 25 and 26 at its upper and lower ends is drilled to provide holes, and the bars of each pair are adjustably connected together by means of turnbuckles 29 extending transversely above and below the pack. 105 Each turnbuckle has oppositely extending turnbuckle rods 30 which are threaded at their ends and extend through the holes in the upper and lower ends of the bars 25 and 26. By means of adjusting nuts 31 on the ends 110 of the rods 30, the bars 25 and 26 at their upper and lower ends may be drawn together against the opposite sides of the pack so as to compress or squeeze the constituent sheets 115 thereof together at each end. Where the pack is of different widths the turnbuckle may be first adjusted so as to approximate in length the width of the pack, and the final adjustment to tighten the bars against the pack is accomplished by means of the upper and lower adjusting nuts 31 on the opposite ends of the turnbuckle rods 30. 120

Each bar 25 and 26 is provided with a vertical series of spaced holes 32 so that where the sheets are of different widths or the bundles are of different heights, the turnbuckle rods 30 may extend through any of the series of holes, thereby enabling the upper turnbuckle to be positioned as close as possible to the upper edges of the sheets without, how- 125

ever, engaging them. Secured to each bar 25 and 26 is a steel eye loop 33 by means of which the bundle, as hereinafter described, may be lifted or lowered through the medium of the crane or stack lifter. Each loop or sling 33 comprises a steel bar or strap bent upon itself to provide an eye to receive the hook of the hoisting mechanism of the crane or stack lifter. The flat shank 33^a of the loop is provided with a pair of holes 33^b spaced in accordance with the holes 32 in the bars 25 and 26, and it will be seen that the loop may be adjustably secured at different heights to each bar 25 and 26 by means of a pair of bolts and nuts 34 extending through any of the pairs of holes 32.

From the foregoing it will be seen that the bars 25 and 26 of each set may be drawn together at the upper and lower ends thereof so as to squeeze or compress the pack transversely adjacent each end thereof. Upon hoisting the pack by means of the eye loops 33, the weight of the pack will be sustained by the bars 25, 26 and 28, which are connected together through the medium of the steel stirrups, loops or straps 27. The lifting strain will be taken entirely by these elements, and none of the strain will be transmitted to the turnbuckle parts 29 and 30.

The pack or bundle may also be clamped or bound intermediate the sets of bars 25 and 26 such as by means of a pair of vertical I-beams or bars 40 and 41 positioned at opposite sides of the bundle. These bars are connected together at the top and bottom thereof by means of turnbuckles 42, each having oppositely extending threaded rods 42^a extending through any of a series of spaced holes 43 in each bar. It will be seen from this construction that the I-bars 40 and 41 may therefore be adjusted and clamped against the opposite faces of the sheets either by operating the turnbuckle proper or the adjusting nuts 44 on the outer ends of the turnbuckle rods 42^a, the turnbuckles and adjusting nuts providing a compound adjusting means for the clamp or compression bars.

Bearing against the upper and lower edges of the sheets of the pack S are a pair of lengthwise spaced wooden bars or members 45 and 46. The lower set of wood members 45 and 46 are of sufficient thickness to sustain the weight of the sheets of the pack S and each upper and lower set of bars 45 and 46 is connected at opposite ends thereof to the bars 40 and 41 by means of clamps 47, four clamps being provided and each preferably identical in construction. The clamp 47 comprises a steel plate formed with opposite vertical side flanges 48, and the outer edge of the plate is slotted and formed with a recess 49, the metal being bent up to provide a vertical flange 50. The plate at opposite sides adjacent the base of the flange 50 is notched to provide recesses 51, and the construction is such that the I-bars 40 and 41 will fit into the recess 49 with

the flanges 40^a or 41^a of the I-bars fitting into the notches 51 and embracing opposite edges of the plate 50, the latter abutting against the central web 40^b or 41^b of the I-bar. The ends of the wooden members 45 and 46 are confined between the flanges 48 and the opposite edges of the flange 50 and project at opposite sides of the I-bars 40 or 41. The flange portion 50 is provided with a vertical elongated slot 50^a through which freely passes one of the turnbuckle rods 42^a.

The foregoing binding devices, comprising the members 40, 41, etc. with the transverse wood bars or members 45 and 46 positioned above and below the pack, are especially adapted for use in connection with the shipment of packs or bundles of metal in a carrier with the constituent sheets thereof resting on their edges, the wood bars or members serving to restrict the longitudinal displacement or movement of the constituent sheets when the carrier is in transit. This very desirable feature of my invention will be referred to more fully hereinafter.

After the pack has been bound together as a unit and in such condition is resting upon the buck or loading apparatus as shown in Fig. 7, to transfer such bound pack from its position upon the buck to the storage warehouse or elsewhere, it is simply necessary to move the hoist hook of a crane or other lifting mechanism V into close proximity to the pack. The hoist hook is provided with a chain, the opposite ends of which are adapted to be engaged with the loops or eyes 33 at opposite sides of the pack. The pack is lifted from its inclined position upon the buck as shown in Fig. 7 in such manner as to swing the pack from an inclined to a vertical position, and the pack may then be conveyed to storage as shown diagrammatically at the right of Figure 8. It will be seen that the bundle or pack S is resting upon the wood members 45 and 46 and that the lower edges of the sheets of the pack are maintained out of contact with the floor.

When it becomes desirable to transfer the bound packs of units from the storage warehouse to the carrier or elsewhere, the crane is employed to again lift the bound pack or bundle and place it in position upon the lift platform L of an industrial truck T. This operation is shown diagrammatically in Figure 8. The hooks carried by the ends of the hoist chain are then disengaged from the eyes 33 whereupon the bundle or pack S may be propelled by means of the lift truck T directly from the storage warehouse across the landing or loading dock D and through the door E of a box car C and transferred from the lift truck platform L to the car floor by means of one of my improved stack lifters, shown at U in Figs. 9, 10 and 11, which has been previously positioned with in the freight car C.

Referring particularly to Figs. 10 and 11, it will be seen that my improved stack lifter U which is preferably constructed as shown and described in my co-pending application Serial No. 133,374 filed September 3, 1926, 6 comprises an arched frame including two spaced pairs of legs 60 and 61 which are spaced apart sufficiently to straddle a pack or bundle S and also to permit the truck platform L to be introduced therebetween as 10 shown in Fig. 11. Each leg comprises a pair of spaced vertical structural members which are connected together at the lower ends thereof by means of a foot or bearing plate 62. Thus it will be seen that the four 15 legs of the stack lifter are provided with a large bearing surface so that when positioned upon the car floor, the device is permitted to lift a ten ton pack or bundle of metal without the danger of breaking through the car floor. The legs at the upper ends thereof are united together by means of a super- 20 structure 63 within which the hoisting mechanism is carried, and the stack lifter is of a 25 height to permit it to be propelled through the doorway E of the car.

The hoisting mechanism in general comprises an electric motor and gear reduction mechanism (not shown) mounted on the super-structure and connected to a central cross shaft 64 carrying a pair of small sprockets 65. Connected to these sprockets are oppositely extending sprocket chains 66 and 67 which are connected at their outer ends respectively to relatively large sprockets 68 and 69. The sprocket 68 is secured to a cross shaft 70, and the sprocket 69 is secured to a cross shaft 71. These shafts 70 and 71 each carry at opposite ends a pair of hoisting drums 72, each having a hoisting cable 73 operating through a sheave block 74 provided with a hook 75 adapted to be connected with the eyes or loops 33 of the bundle.

The power mechanism is provided with suitable controls for enabling the four hoisting drums to raise or lower a bundle of metal, and power is conducted to the electric motor of the stack lifter by means of conductors or cables 76 directly from the battery of the electric truck Γ (see Fig. 11). The stack lifter is provided with four swiveled casters 77 to permit the lifter to be wheeled or propelled within the freight car or elsewhere when a pack or bundle is not supported by the lifter. Each of these casters is carried by a revolving spindle, and by means of compression springs 78 of predetermined strength, the stack lifter without a load will be supported solely upon the casters. When, however, a load is lifted or supported by means of the hoisting mechanism, the springs 78 and hence the casters will yield to permit the combined weight of 65 the stack lifter and load to be supported upon

the legs 60 and 61 as shown in Fig. 11, thereby providing a substantial distribution of the load upon the floor and enabling loads such as ten tons in weight to be bodily lifted without breaking through the car floor. To 70 prevent the casters 77 from turning and becoming jammed between the wall of the freight car and a pack or bundle, the casters may be locked against turning by means of lock bolts 79. The stack lifter U is also provided with two sets of swiveled or swinging dogs 80 to enable the truck platform L when introduced between the legs 60 and 61 to lift the stack lifter bodily on the truck platform. When the four dogs 80 are swung into 80 the position shown in full lines in Fig. 10 so as to project inwardly over the truck platform L, said platform, when elevated by the power mechanism of the truck, will engage the bottom portions 80^a of the dogs. 85 Thus the stack lifter will be elevated from the floor by the truck and carried from point to point through the medium of the lifting dogs 80. The stack lifter U is preferably constructed substantially in the manner 90 shown and described in my above mentioned co-pending application.

From the foregoing it will be seen that after the stack lifter U has been carried into the car by means of a lift truck platform L 95 and lowered into position to be supported through the medium of its casters 77 upon the car floor, it may be rolled into position to straddle the floor space where it is desirable to position, for transit, a bound pack 100 or bundle S. At this stage of the method of loading the pack or bundle into the car, I place at predetermined spaced intervals transversely of the car floor, a series of wood bars or pallet members P which form the 105 supporting means for the bound pack or bundle when it is positioned upon the car floor.

With the transverse members P of the pallet in their proper positions upon the car 110 floor and with the legs of the stack lifter straddling the space upon which the bundle is to be positioned, a bound pack or bundle S is brought into the car upon the lift platform L of a truck and moved into position between the legs 60 and 61 of the stack lifter. The hoisting hooks 75 are then engaged with the loops or eye members 33 and the hoisting mechanism operated to lift the bundle as a 115 unit from the lift platform L. The truck is then backed out from its position within the stack lifter frame, and the hoisting mechanism further manipulated to lower the bound pack into position upon the car floor to be supported thereupon by means of the pallet members P. After the weight of the bundle has been transferred to the pallet members P, the hooks 75 are released from the bundle and the weight of the stack lifter is again transferred to its supporting casters 77. The stack 120 125 130

lifter is then rolled out so as to be free of the bundle and its supporting pallet members. The buttresses F may then be positioned against the opposite ends of the pack S.

It will be noted (Fig. 13) that the pallet members P are of sufficient thickness to support the pack or bundle S above the floor with the binders or bracing apparatus at opposite ends of the pack out of contact with the floor. It will be noted, however, that the wood bars 45 and 46 extending beneath the pack are of a sufficient thickness, together with the clamps 47 to fill the space between the car floor and the under side of the bundle at its intermediate portion. Therefore, it will be seen that the wood bars 45 and 46 sustain a portion of the weight at the intermediate section of the pack, and that the weight of the pack upon the wood bars is sufficient to cause the constituent sheets to bite into the relatively soft bars causing a frictional engagement and restricting longitudinal movement or displacement of the sheets.

I have found that when the freight car is subjected to severe blows or shocks, the tendency of the bundle or pack to move in the car longitudinally is not in a straight horizontal direction but rather the pack tends to rock or weave. One end of the pack will tend to lift slightly relatively to the other end before shifting longitudinally. With the sheets supported on edge, this shifting action is resisted by the sheets biting or digging into the wood supports or pallet members P and also by their engagement with the wood members 45 and 46 clamped to the under side and top of the bundle at its intermediate portion by means of clamps 47.

Referring particularly to Fig. 14, the rocking movement of the pack in one direction is shown in dotted lines. Since the members 45 and 46 are spaced at opposite sides of the center of the pack, greater upward pressure will be exerted against the member 46, for example, than the member 45, resulting in binding or compressing the member 45 under great pressure against the upper edges of the constituent sheets of the pack so that the sheets will not only embed themselves in the wood surface of the member 45 but also in the member 46, thereby resisting the tendency of the pack to shift on the car floor. Due to the relatively soft character of the material, this action will not result in crimping the edges of the sheets. The bars 40 and 41 have a slight clearance at opposite sides in the recess 49 thus enabling the clamp 47 to rock slightly about the axis of the turnbuckle rod 42. This limited relative movement compensates for any weaving or rocking action of the pack resulting in an efficient compressing action of the wood members 45 and 46 against the edges of the sheets when the car is subjected to collisions or shocks.

From the foregoing it will be seen that by

my method and improved apparatus for carrying out the method, sheet metal after the final operation at a mill, may be bound into packs and transferred to storage or to a carrier for shipment, in a comparatively simple manner, with a minimum of labor, expense and handling costs, and that such bound packs or bundles may be shipped in the carrier and maintained in compact units during transit, without danger of damage to the sheets or damaging the freight car during transit, and that at destination the packs or bundles are intact and may be removed as individual units without the necessity of breaking up the packs and manually handling the constituents parts thereof.

What I claim is:

1. The method of loading sheet metal on the floor of a freight car for transportation, which comprises supporting the sheets of a pack to be bound with the sheets resting on edge in inclined planes, conveying the pack with the sheets in upright positions into the car, and transferring the bound pack to the car floor with the sheets disposed on edge in vertical planes.

2. The method of loading sheet metal on the floor of a freight car for transportation, which comprises supporting the sheets of a pack to be bound with the sheets resting on edge in inclined planes, conveying the pack with the sheets in upright positions into the car, transferring the bound pack to a supporting medium for the pack, and depositing the pack by means of said supporting medium on the car floor with the sheets disposed on edge in vertical planes.

3. The method of loading sheet metal in packs on the floor of a freight car for transportation, which comprises supporting the sheets of a pack after the sheets are stacked with the sheets resting on edge in inclined planes, conveying the bound pack with the sheets in upright positions to the car, transferring the bound pack to a lifting medium, and depositing the pack on the car floor by means of said lifting medium with the sheets disposed on edge in vertical planes.

In testimony whereof I affix my signature.

ROBERT T. ROMINE.
